SELF-SEALING CONTAINER CLOSURE

Floyd A. Terwilliger, 1264 Culver Road, Rochester, N.Y.

Filed Mar. 31, 1960, Ser. No. 59,967

Term of patent 14 years

(Cl. D58—26)

FIG. 1.

FIG. 2.

FIG. 3.

FIG. 4.

FIG. 1 is a side elevation of a self sealing container closure embodying my new design;

FIG. 2 is a top plan view thereof;

FIG. 3 is a bottom view thereof; and

FIG. 4 is a vertical sectional view thereof.

I claim:

The ornamental design for a self sealing container closure, substantially as shown.
